UNITED STATES PATENT OFFICE.

CHARLES S. FRENCH, OF ECKMAN, WEST VIRGINIA.

SAND-DRIER.

1,276,514.

Specification of Letters Patent. Patented Aug. 20, 1918.

Application filed January 7, 1918. Serial No. 210,763.

To all whom it may concern:

Be it known that I, CHARLES S. FRENCH, a citizen of the United States, residing at Eckman, in the county of McDowell and 5 State of West Virginia, have invented certain new and useful Improvements in Sand-Driers, of which the following is a specification.

This invention relates to sand driers and 10 has special reference to sand driers of the type shown in Letters Patent No. 933,898, granted to me September 14, 1909. The object of the present invention is to simplify the construction of the drier so as to reduce 15 the cost of building the same and also improve the operation, a particular aim of the invention being to reduce the liability of the fire box to warp under the heat therein.

The invention is illustrated in the accompanying drawings and consists in certain novel features which will be first fully described and then more particularly pointed out in the appended claims.

In the drawings:

25 Figure 1 is a perspective view of a sand drier embodying my present improvements.

Fig. 2 is a longitudinal sectional view of the same.

Fig. 3 is a transverse section on the line 30 3—3 of Fig. 2,

Fig. 4 is a transverse section on the line 4—4 of Fig. 2.

In building a sand drier in accordance with my present invention, I employ an 35 ash-pan or pit 1 which will preferably be a metallic rim provided in its front end with an ash door 2 and provided at its rear end with an air inlet 3. The ash-pan may, of course, have a bottom but such bottom is 40 not essential and is not illustrated, as the rim defining the ash-pan may rest directly upon the ground. A floor 4 is provided at the top of the ash-pan and defines the front and rear portions of the drier, grate bars 45 being supported by flanges 6 on the floor over the ash-pan so as to support fuel in the usual manner. The front floor member 4 terminates short of the vertical side walls 6' of the fire box thereby providing a space 50 or flue 7 through which air may flow, as indicated by the arrows in Figs. 2 and 4. The said front floor member constitutes the bottom of a fuel chute or passage 8 through which fuel may be inserted into the fire box 55 and the said chute or opening will be normally covered by a door 9 provided with a

damper 10 for regulating the draft. The side walls of the fire box extend vertically upward to a point above the top of the fuel opening or passage 8 and then diverge outwardly at their front ends, as shown at 11, upwardly converging roof plates or deflectors 12 being supported by and extending from the outer edges of the said divergent portions. Below and between the diverging 60 portions 11 of the side walls, top or roof plates 13 converge upwardly from the side walls and these plates are supported at their ends in grooved projections 14 provided upon the front and rear end walls 15 and 16 of the fire box, as shown most clearly in Fig. 2. Reinforcing ribs 17 will preferably be provided on the inner sides of the said top plates 13 so as to tend to overcome 65 buckling or warping thereof. The front 70 wall 15 of the fire box is located at the inner end of the fuel passage 8 and the space between said wall and the front wall 24 of the drier forms the flue 7, said walls extending above the roof plates 13, and supporting 75 the roof plates 12 at their upper edges.

A deflector 13' bridges the flue 7 approximately in the planes of the roof plates 13. The front wall 15 of the fire box is provided above the fuel opening 8 with a plurality 80 of openings 18 through which the air rising through the flue or passage 7 and diverted by the deflector 13' may enter the upper portion of the fire box and flow rearwardly below the top plates 13 thereby preventing 85 the overheating of said top plates and prolonging the life of the drier. The lower portion of the rear wall 16 is imperforate so that the heat cannot pass directly backward into the flue or space 19 formed be- 90

tween the fire box and the outer jacket 20 but must rise so as to pass through the opening 21 in said rear wall. Between the rear wall 16 and the rear wall of said jacket I provide roofing plates 35 which cover the 100 flue or space between said walls, but the space between the front and rear walls 15 and 16 above the roofing plates 13 is left unobstructed, except as will be presently set forth. The space between said front and 105 rear walls is thus left open to facilitate the loading of sand into the drier, while the inclined plates or roofs constitute deflectors to insure proper circulation of the air currents so as to utilize the heat to the greatest 110 advantage and quicken the drying of the sand. The roofing plates 35 terminate at a

flue outlet 36 and a horizontal deflector or partition 37 bridges the flue at the base of said outlet. Like the front wall 15, the rear wall 16 is extended vertically above the 5 plates 13 and in the extended portions of said walls are provided suitable triangular openings 22 for the passage of the air currents, and extending between said extensions of the front and rear walls are horizontal longitudinal flues 23 which are inverted V-shape in cross section and are disposed in series extending substantially parallel with the extreme upper edges of the end walls, as shown clearly in Figs. 3 and 4. 10 By reference to said figures, it will be readily noted that the flues serve as deflectors to prevent the sand passing directly downward and cause the same to turn toward the sides of the drier so that it will be more extensively exposed to the action of the heat and will be therefore quickly dried. The jacket 29 surrounds the rear end and the two sides of the drier and is arranged in spaced relation thereto. The front end of 15 this jacket is disposed flush with the front plate 24 of the drier which constitutes the front wall of the flue 7 and on which the door 9 is hung. This jacket may be constructed of sheet metal and has vertical side portions 25 which extend from the horizontal plane of the grate 5 to points at or slightly above the lower edges of the top plates 13 of the fire box at which points the said side walls diverge, as shown at 26, 20 to conform to the front and rear end diverging portions 11 of the side walls of the fire box and thence extend vertically upward, as shown at 27. The end walls of the jacket conform to and extend above the roofing plates 12, as shown at 28. A smoke stack 29 is fitted upon the upper extremity of the flue outlet 36 and may lead to any desired point so as to carry off the vapors and products of combustion. The corners of the 25 jacket are reinforced by angle irons 32 which are riveted or otherwise firmly secured to the meeting portions and tension bars or bolts 33 are extended longitudinally and transversely through the drier and secured in the walls of the jacket so as to hold the same against undue expansion. Spacing sleeves or tubes 40 may be fitted around the stay bolts between the walls so as to brace the walls against buckling. The 30 lowermost transverse bolts, of course, terminate at the sides of the fire box as shown in Figs. 3 and 4.

To the lower edges of the jacket I hinge the angular doors 31 which have inwardly projecting flanges or shelves 41 at their lower edges, said shelves being provided with perforations 42 so that they will serve as screens to permit escape of the dried sand. The doors may be held in the closed 35 sand-supporting position by any convenient

means and may be readily swung downward when necessary to remove obstructions such as stones, sticks or clods which may be in the sand.

It is thought the use of my improved 70 drier will be readily understood from the foregoing description taken in connection with the accompanying drawings. A fire is kindled in the fire box in the usual manner and the sand is loaded by any preferred 75 means into the top of the drier above the horizontal flues 23. Cold air will, of course, enter the ash-pan through the opening 3 in the back end thereof and some of the air will pass through the grate 5 and support 80 combustion of the fuel, the heat passing upwardly through the opening 21 into the flue 19, whence it will be deflected by the deflector 37 and roofing plates 35 through the openings 22 which are located below the 85 plane of said deflector and flow forwardly through the lower flues 23 to the vertical flue 7 above the deflector plate 13' therein. The heated currents will then rise through said flue 7 and be turned rearwardly by the 90 deflector or roof 12 so as to flow rearwardly through the upper flues 23 and enter the flue outlet 36 and thence escape through the smoke pipe 29. A considerable portion of the air entering the ash-pan will flow to 95 the front end thereof and rise through the flue 7 around the fuel passage 8 and then escape through the openings 18 into the upper portion of the fire box, flowing rearwardly just below the rod 13 and mingling 100 with the products of combustion passing through the opening 21. The air which passes upwardly through the passage 7 and escapes through the openings 18 will be cooler than that passing up through the 105 grate and will consequently tend to prevent overheating of the roofing plates so that warping of the said plates will be avoided. The sand will move by gravity to the bottom of the jacket and will accumulate 110 around the open-bottom flues 23. The entire body of sand will, consequently, be exposed to the action of heat and the greater portion thereof will be subjected to the direct action of the air currents flowing along the 115 said flues so that the moisture is rapidly withdrawn from the sand and carried off. As the sand dries it will settle to the bottom of the jacket and escape through the perforations 42. My improved construction provides for 120 a very complete and effective circulation of the heated currents and avoids overheating of the roof of the fire box, while, at the same time, a very rapid and thorough drying of the sand is accomplished. A large 125 volume of sand may be dried in a short time with an economical consumption of fuel.

Having thus described the invention, what is claimed as new is:

1. In a sand drier, the combination of a 130

- fire box, vertical walls arranged in spaced relation to the front and rear end walls of the fire box, there being openings in the front and rear walls of the fire box 5 communicating with the space between the fire box and said walls, an air inlet below the fire box in communication with the space between the front end of the same and the said front wall, deflectors in the space between the said front wall and the front end of the fire box following the lines of the top of the fire box, a deflector in the space between the rear end of the fire box and the rear vertical wall and disposed 10 above the top of the fire box, and horizontal flues disposed above the fire box and in communication with chambers above the respective deflectors.
2. A sand drier comprising a fire box, vertically disposed flues at the front and rear of the fire box, the lower end of the rear flue being closed, openings in the upper portion of the front end rear walls of the fire 15
- box to establish communication with said flues, the lower portion of the rear wall of the fire box being imperforate, deflectors in said flues, horizontal flues connecting the vertical flues, and a smoke stack leading from the rear flue. 25
3. A sand drier comprising a fire box, a jacket disposed in spaced relation to the sides and rear of the fire box whereby to provide sand containing chambers, and discharging doors disposed longitudinally of the sides of the jacket and adapted to support sand between the same and the sides of the fire box. 30
4. A sand drier comprising a fire box having vertical sides and upwardly converging top plates, flues at the front and rear of the fire box in communication with the front and rear ends of said fire box, and reinforcing ribs formed on the under surface of the upwardly converging top plates. 40
- In testimony whereof I affix my signature. 45
CHARLES S. FRENCH. [L.S.]
